UNITED STATES PATENT OFFICE.

LOUIS N. D. WILLIAMS, OF OGONTZ, PENNSYLVANIA, ASSIGNOR TO SCOTT & WILLIAMS, INCORPORATED, OF NEW YORK, N. Y., A CORPORATION OF MASSACHUSETTS.

METHOD OF TRANSFERRING KNITTED FABRICS AND MECHANISM FOR THIS PURPOSE.

Application filed December 1, 1925. Serial No. 72,483.

This invention is concerned with transfer of knitted fabric from the needles of a producing machine to a transfer device capable of placement in other machines adapted to 5 perform subsequent operations upon the web in furthering the manufacture of articles of knitted ware. One instance of the usefulness of transfer mechanism of the character referred to, is in connection with seam- 10 less hosiery knitting machines (employing either latch or spring beard needles) to accomplish an intermediate step pre-requisite to the closure of the toe pocket of the stocking; that is to say, to transfer the pocketed 15 tubular web to a split point ring capable of subsequent placement in a sewing machine of the kind shown and described in my Patent No. 1,815,064, designed to automatically close the toe pocket by uniting doubled loops of 20 its opposite halves. I have accordingly hereinafter described my invention with reference to this specific use, although, as will be apparent from further explanation, it may be as readily employed with corresponding 25 advantages, in other instances involving or necessitating a transfer operation.

The main object of my invention is to enable a transfer step of the character mentioned to be accomplished entirely automatically so as to dispense with the necessity for dependence upon special or skilled labor as has generally been the case heretofore; and to secure this desideratum by mechanism useful in connection with standard stocking 30 knitting machines such as exemplified in the U. S. Patent of Robert W. Scott, No. 1,152,850, September 7, 1915, known in the trade as the "Scott and Williams machine", and of Joshua D. Hemphill, No. 933,443, September 7, 1909, 35 known as the "Banner" machine. These machines are typical of the kind now ordinarily used, and are generally similar in that they comprise a cylinder with needles and cooperative sinkers, means to rotatably oscillate 40 the cylinder during the knitting of the stockings, etc. Such machines, however, differ in one respect, to-wit:—in the Scott type machine the needle cylinder is bodily moved 45 with respect to the knitting cams for the purpose of fashioning the stocking leg and ankle through variation in the size of the loops drawn by the needles, while in the Hemphill type machine, this same function is performed in a converse manner, i. e., by moving

the knitting cams bodily with respect to the 55 needle cylinder.

Another aim of my invention is to utilize the relative movement between the needle cylinder and knitting cams—as well as other characteristic motions inherent to such standard knitting machines—in performing certain useful phases of the transfer operation.

A further object of my invention is to attain the foregoing advantages, together with others which will appear from the detailed 65 description hereinafter, in fabric transfer mechanism having the form of an attachment capable of being applied to standard knitting machines without requiring any alteration whatever in them, either with regard to their 70 construction, or their normal cycle of operations incidental to the knitting of stockings.

Referring to the drawings, Fig. I is a front view of a Scott type knitting machine equipper with my improved transfer mechanism.

Fig. II is a plan view of the organization shown in Fig. I.

Fig. III is an elevation looking toward the left hand side of Fig. I.

Fig. IV is an elevation of the left hand side of Fig. I.

Fig. V is a partial front elevation of the machine showing the carrier for the transfer ring lowered in readiness for transfer of 85 fabric from the needle cylinder to the looping points of said ring.

Fig. VI is a fragmentary sectional view showing certain important details of the transfer ring carrier.

Fig. VII is a partial plan sectional view, taken as indicated by the arrows VII—VII in Fig. V, showing the means for temporarily locking the needle cylinder against rotation during fabric transfer.

Fig. VII^a is a detail sectional view, taken as indicated by the arrows VII^a—VII^a in Fig. VII.

Fig. VIII is a fragmentary sectional view showing the means provided in the Scott 100 machine to retract the stitch drawing cams for needle leveling.

Fig. IX is a sectional view, taken as indicated by the arrows IX—IX in Fig. V, showing the transfer ring carrier in position and 105 with the ring poised above the needle cylinder of the machine in readiness to receive the fabric.

Figs. X and XI are axial sectional views, taken at right angles to the plane of Fig. IX, and showing successive positions of the various parts incidental to fabric transfer.

5 Figs. XII and XIII are plan sections, taken as respectively indicated by the arrows XII—XII and XIII—XIII in Fig. IX.

Fig. XIV, Sheet 6, is a perspective view of a split transfer ring (generally similar to that shown and described in my Patent No. 1,348,195, August 3, 1920) conveniently employable in connection with the transfer mechanism of my present invention.

Figs. XV, Sheet 6, and XVI, Sheet 8, are detail sectional views, taken as respectively indicated by the correspondingly identified arrows XV—XV and XVI—XVI in Fig. XII.

Fig. XVII is a fragmentary sectional view 20 of the machine showing the manner in which the needle cylinder is elevated, to the position corresponding to that of Fig. XI, in the act of restoring the transfer ring to its original position in the carrier.

25 Fig. XVIII is a sectional view, taken as indicated by the arrows XVIII—XVIII in Figs. IV and XXIII, showing the means for moving the ejector to active position in readiness to displace the finished fabric from the machine.

Fig. XIX is a partial development of the cam shell of the machine showing certain additional provisions facilitating transfer in accordance with my invention.

30 Fig. XX is a partial plan sectional view of the cam shell with the additional adjuncts.

Fig. XXI is a diagrammatic view showing the special picker control means illustrated in Fig. XX.

40 Fig. XXII is a fragmentary view in plan of the means whereby the various instrumentalities of the transfer mechanism are controlled and timed.

Fig. XXIII is an elevation of the assemblage shown in Fig. XXII.

45 Fig. XXIII^a, Sheet 4, is a fragmentary view of certain parts associated with the mechanism shown in Figs. XXII and XXIII, and as conveniently indicated by the arrows XXIII^a appearing in the former of said figures.

Fig. XXIV is a development of one of the drums included in the control mechanism of Fig. XXII.

50 Fig. XXV is an axial sectional view of the drum aforesaid.

Fig. XXVI is a plan sectional view of the drum, taken as indicated by the arrows XXVI—XXVI in Fig. XXV.

55 Fig. XXVII is a detail section, viewed in the direction of the arrows XXVII—XXVII in Fig. XXVI.

Figs. XXVIII and XXIX are fragmentary illustrations showing successive 60 positions of the means for automatically shift-

ing the drive belt to restart the machine after completion of the transfer operation.

Fig. XXX is a plan view of the special sinker cam ring which I employ for the purposes of my invention.

Figs. XXXI and XXXII, Sheet 14, are similar views with the component parts in different positions.

Figs. XXXIII and XXXIV, Sheet 13, as well as XXXV, Sheet 14, are diagrammatic views showing the different positions of the sinker control cams respectively in accordance with Figs. XXX, XXXI and XXXII.

Fig. XXXVI, Sheet 14, is a detail sectional view taken as indicated by the arrows XXXVI—XXXVI in Fig. XXX, Sheet 13.

Fig. XXXVII shows the normal cooperative relation between a needle and the corresponding sinker during ordinary knitting.

Fig. XXXVIII is a view similar to the preceding, but showing the fabric loop penetrated by a point of the transfer ring and ready to be cast for retainment by the latter.

Fig. XXXIX shows the relation of the needle sinker and point ring during loop casting.

Fig. XL is a similar view showing the relation of the same instrumentalities after loop casting.

Fig. XLI, Sheet 3, is a detail view of the mechanism for moving the latch guard ring of the machine to inoperative position.

Fig. XLII, Sheet 3, is a similar view showing the parts of the above mechanism in different positions.

Fig. XLIII, Sheet 4, shows the details of the means for controlling the ejection of the finished stocking blank.

Fig. XLIV, Sheet 4, is a view similar to the preceding, but with the parts in different positions.

Fig. XLV, Sheet 1, is a detail sectional view showing the details of the fabric ejector.

Fig. XLVI, Sheet 15, shows a sectional view through the needle cylinder and associated parts of the type of knitting machine shown and described in the Hemphill patent hereinbefore referred to, and illustrating the manner in which certain phases of the transfer operation are effected on such a machine in accordance with my invention.

Fig. XLVII is a fragmentary sectional view showing the manner in which the needles are separated from the points of the transfer ring after the loops have been cast.

Fig. XLVIII, Sheet 16, shows the special cam which I provide to shift the knitting cam support relative to the needles of the Hemphill machine incidental to fabric transfer; and

Fig. XLIX shows a partial diagrammatic development of the knitting cams of the Hemphill machine.

With reference first to Figs. I, IV and VIII, the knitting machine therein depicted

is generally similar to that shown and described in the Scott patent, supra. Its cylinder 1, which serves to sustain and guide the knitting needles N, is mounted for rotation in a bed plate 2 at the top of the frame 3 of the machine. The cylinder 1 is rotated by gearing journalled on the frame 3, such gearing including a spur gear wheel 4 (Fig. III) that meshes with a pinion 5 fast on the main drive shaft 6, the latter being equipped with the usual tight and loose pulleys 7, 8, respectively, as well as an intermediate pulley 9 employed to drive the cylinder 1 at reduced speed during fashioning of the heel and toe pockets in accordance with customary practice. Shifting of the drive belt between the pulleys 7, 8 and 9 is effected by a spring-pulled shipper 10 slideable on a rod 11 projecting from the frame 3, and under control of a rotary cam 12 fast on a shaft 13, said shaft being intermittently rotated by the pawling mechanism of the machine, and serving in turn to drive, through intermeshing gears 14 (Fig. IV), a shaft 15 which carries the main pattern or cam drum 16. The sinkers S as best shown in Figs. X and XI which cooperate with the needles N are mounted for radial sliding in an annulus 17 secured about the top of the needle cylinder 1. In knitting a stocking, the needles N are actuated by a group of stitch cams 18 (Fig. XIX) with the assistance of lifting or elevating pickers 19-19^a and a drop picker 20, that functions during the fashioning of the heel and toe pockets. The stitch cams 18 are mounted on a segment 21 capable of being retracted laterally from the main section C of the cam shell for needle leveling, by a thrust rod 22, Fig. VIII, that is subject to a cam lug 23 on the main cam drum 16, precisely as in the Scott patent, supra. The main cam drum 16 of the machine controls selective activity of the interchangeable yarn feeds F (Figs. II and III) pivotally mounted on the latch guard ring G, the latter being secured to a shaft 24 so as to be swingable upward, from the normal position to Fig. III to the raised position of Fig. V, when access must be had to the needle cylinder 1, in the present instance particularly to enable transferring. For the purpose of lengthening or shortening the fabric loops as in fashioning the leg and ankle of the stocking, the needle cylinder 1 is bodily movable with respect to the knitting cam shell C (see Fig. XVII) under guidance of an axial sleeve 26 integrally formed with the bevel gear 27, by which said cylinder is coordinated with the drive mechanism of the machine. Vertical movement is imparted to the cylinder 1 by a pin 28, that extends through the gear 27 and engages the top of a tubular fabric receiver 29, beneath the bed plate 2. This fabric receiver 29 is sustained for vertical movement through guidance of

its upper end in a depending flange of the bed plate 2, and its lower end in an aligned annulus 30. At one side, the fabric receiver 29 has a lug 31 adapted to be engaged by a projection 32 of an arm 33, in the path of a special lug 34 on the main pattern drum 16.

With this brief summary of the Scott machine, I will now proceed to describe the manner in which my improved transfer mechanism is employable therewith. The power necessary to drive this transfer mechanism is derived from a pulley 35, Fig. IV, on a line shaft 36, which also carries a pulley 37 to normally drive the machine by means of a belt 38, Figs. III and IV. Motion is transmitted from the pulley 35 by a belt 39 to an aligned pulley 40, Figs. II and IV, secured on a shaft 41 appropriately journalled in a bracket 42 which is bolted or otherwise secured to the frame 3. The motion of the shaft 41 is in turn transmitted, through a pinion 43 and gear 44, to a shaft 45 also journalled in the bracket 42. The gear 44 carries a crank pin 44^a which is coordinated by a link 46 with a rocker arm 47 on another shaft 47^a, to the shorter extremity of which rocker arm is pivoted a pair of pawls 48, 49. On its upward strokes, the pawl 48 successively engages pins 50 projecting from the gear 4 previously referred to, while during its idle downward strokes the companion pawl 49 successively picks pins 51, on the back of a gear 52 in direct mesh with the gear 4, and of the same pitch diameter. Although the pawl 48 would alone suffice to step about the cylinder 1 for the purpose explained, I preferably employ the additional pawl 49 and the gear 52 to reduce the time interval necessary for accomplishment of such progression, not only in order to expedite transfer, but to shorten the periods of idleness of the machine between knitting of successive stocking blanks. During normal operation of the machine, the pawls 48, 49 are held inactive by laterally projecting pins 53 of a lever 54 fulcrumed, intermediate its ends at 55, to a suitable bracket attached to the frame 3. A lug 56 on the lever 54 is acted upon by circumferential projections 57, 57^a of a rotary cam 58, secured to the shaft 13 with the belt 110 shipper control cam 12, engagement between said lug 56 and cam 58 being at all times maintained by a spring 59 drawing upon the shorter end of the lever 54.

For the purposes of my invention, I employ, in addition to the standard equipment of the machine for progressing the cam shaft 13, a supplemental shifting means which includes a pawl 60 designed to engage peripheral projections 61, 62 on the rotary cam 12. The pawl 60 is pivoted to an arm 63 that oscillates freely on the shaft 15 of the main or pattern drum 16, and receives its rocking movement directly from the pawling mechanism of the machine. Oyerthrow 130

of the needle cylinder 1 under the picking of pawls 48, 49 is prevented by a brake arm 64 designed to engage the tight pulley 7 during this time, said brake arm being fulcrumed for independent movement on the protruding end of the shaft 15 and shifted to active position incidental to downward movement of the lever 54 in releasing the pawls 48, 49, through engagement of one of the pins 53 with a leaf spring 65 projecting rearward from the brake arm shoe.

The transfer ring R (Fig. XIV), as previously stated, is of the kind adapted to be inserted in a sewing machine whereby the toe pocket of the stocking is subsequently closed, and to this end comprises the two shell parts or sections 66, 66^a whereof the latter is swingable over the former about hinges 67 to enable registry of its looping points P with the corresponding points of the other section for doubling of the fabric loops preparatory to the sewing. It is to be understood that means (not shown) are provided for normally holding the parts 66, 66^a locked, in the open position illustrated, to provide a complete circle of points P for receiving the fabric loops from the needles N. Associated with the transfer device or ring R is a stripper T comprising a pair of semi-circular members 68, 68^a, (respectively coordinated with the sections 66, 66^a) which together constitute an annulus having peripheral notches set apart by intervening projections that extend outward between the looping points P, see Fig. IX. The stripper members 68, 68^a are each supported by a pair of rods 69 which are slidably inward flanges of the sections 66, 66^a and joined beyond by arcuate plates 70, 70^a accessible from within the ring R for actuation as hereinafter explained. In the present connection, the stripper T does not actually function as such, but as an advance guard to insure, through the instrumentality of its peripheral notches, alignment of the needles N of the machine with the looping points P as the ring R is lowered onto the needle cylinder 1, as will be readily apparent from further description.

The office of supporting the ring R during transfer is relegated to a carrier 71 shown as secured for swinging movement, to a shaft 72 journaled in an upstanding lug of a bracket 73, which is bolted to the bed plate 2 of the machine. The arm 74 of the carrier 71 terminates in an annulus 75 with a depending cylindric shell or head 76 capable of snugly receiving the transfer ring R after the manner shown in Fig. IX. Retainment of the transfer ring R in the head 76 is by means as follows: As shown in Fig. XIV, the section 66 of the transfer ring R has, adjacent its top, a circumferential groove 77 which is approached through diametrically disposed notches 78 that are registerable with pins 79 projecting

inwardly through slots 80 in the cylindric head 76. Thus, as the transfer ring R is inserted into the head 76 and slightly rotated incidentally to advance the diametrical notches 78 beyond the province of the pins 79, it is subsequently retained through cooperation of said pins with the groove 77. To prevent accidental release of the transfer ring R during downward movement of the carrier 71, as well as to insure its proper positioning for accurate registry of the looping points P with the needles N, I provide a locking means in the form of a bolt 81—shown in Figs. XII, XIII and XV. This bolt 81 is slidable in a guide 82—and normally urged downward by a spring 83 so as to automatically slip into a peripheral notch 84 in the top edge of the transfer ring R when the latter is turned in being inserted into the head 76 of the carrier 71, as above explained.

The carrier 71 is swung and the transfer ring R manipulated incidental to transfer, under control of the timing mechanism generally designated by the numeral 85. By reference to Figs. I, II, III, IV, XXII and XXIII it will be observed that this timing mechanism 85 comprises a pair of cam drums 86, 87 that are intergeared as shown for simultaneous rotation in opposite directions, and supported in suspension by shafts 86^a, 87^a dropped from the bracket 73. Amongst other functions, the cam drum 86 serves to control the locking of the needle cylinder 1 against rotation while the fabric transfer is being made, and, to this end, carries on its top a cam 88 that acts upon a vertically slidable rod 89 to effect swinging movement of a finger 90 which, in turn, imparts downward movement to a locking pin 91 adapted to enter an aperture in the bevel gear 27 carrying the needle cylinder 1, see Figs. V, VII and VII^a, said locking pin being ordinarily held raised by a helical compression spring 92, in an obvious manner. The cam drum 86 has a cam groove 93 for engaging a roller on the shorter arm of a bell crank 94, whereof the larger extremity has the form of a gear sector which meshes with the pinion 95 on the fulcrum shaft 72 of the carrier 71. Consequently, as the cam drum 86 is rotated, the transfer carrier 71 is swung from the position of Fig. I, to that of Fig. V, to lower the point ring R over the needle cylinder 1, and again to return it to the original retracted position after the transfer has been effected, the lowered position of the carrier R being determined by engagement of a set screw 99^a, Fig. VI, on the tail 99 of arm 74, with a lug 73^a on bearing bracket 73. Displacement of the transfer carrier 71 while lowered, is prevented by lock means comprising a bolt 96, Fig. V, that is slidable in a bearing 97, and whose lower end is acted upon by a cam block 98, Fig. XXII, on the top of cam drum 87, said bolt engaging behind a tail piece 99 on the carrier arm 74,

as best shown in the former figure. Manipulation of the transfer ring R in the carrier 71 is controlled by a circumferential cam 100 on the drum 86, said cam acting upon a roller 5 at the outer end of an arm 101, Fig. XXIII. To this arm 101 is pivotally attached a vertical slide rod 102 that has a notched upper end 103, Fig. V, designed to engage a laterally projecting pin 104 of a yoke arm 105 which is fulcrumed at 105^a to the carrier arm 74, when the latter is swung to the lowered position of said figure against the pull of a spring 105^b, Fig. VI. The yoke arm 105 supports in its extremities the transfer ring retaining pins 79 previously referred to. Lifting of the rod 102 by the cam 100 of drum 86 results in actuation of the yoke arm 105 with consequent downward displacement of the transfer ring R relative to the cylindric holder 76 of the carrier 71 from the position of Fig. IX—to that of Fig. X—to engage the points P behind the hooked ends of the needles N and thereby to penetrate the loops held by them. For a purpose to be later described, the cam 100 is given capacity to yield downwardly by virtue of attachment to a spring influenced rod 106 slidable in a groove in the side of the cam drum 86, see Figs. XXIV, XXV and XXVI.

30 While placing the transfer ring R in the carrier 71, the stripper T usually occupies the position shown in Fig. I, i. e., against the lower end of the ring shell 66, 66^a. In order that said stripper T may perform the aligning function hereinbefore described, it must first be projected to the position of Fig. IX beyond the looping points P before the transfer ring R is fully lowered. This function is performed by a finger 107 (Fig. IV) that 35 is freely fulcrumed on a stud shaft 108, and the free end whereof engages behind a projecting tail 109 of a yoke 110 which is pivoted to the carrier 71 at 110^a, and subject to a spring 111, see Figs. IX and XII. The 40 extremities of the yoke 110 are operatively connected to rods 112, 112^a shiftable axially in said carrier 71, and in turn operative upon the arcuate plates 70, 70^a of the transfer ring R to depress the members 68, 68^a of stripper 45 T relative to the ring shell 66, 66^a. The time of operation of the finger 107 is determined by a cam projection 113 on a supplemental extension 114 of the main cam drum 16, said projection acting upon a depending prolongation 115 of said finger, see Fig. IV. The 50 stripper T is held locked in projected position, during lowering of the carrier 71, by a pivoted latch 116 (Figs. XII and XVI) which is spring pressed to automatically slip 55 into a notch 117 in the rod 112; but as the transfer ring R is depressed from the transfer head 76 of the carrier 71, a laterally-projecting lug 118 on the yoke arm 105 trips said latch with the result that the stripper T is 60 freed, through retraction of the rods 112, 112^a

under the action of the spring influencing the yoke 110.

For the purpose of intermittently progressing the cam drums 86, 87 of the timing mechanism 85, I provide a pawling mechanism 70 which is shown to best advantage in Figs. I, II, III, XXII and XXIII. This pawling mechanism derives its motion from the shaft 45 (Fig. III) described in connection with the auxiliary drive for the machine, said 75 shaft transmitting movement, through bevel gears 119, to a vertical shaft 120, to the upper end whereof is fixed a disc 121 with an eccentric stud. A horizontal link 122 connects the eccentric stud of disc 121 with a corresponding stud on a horizontally oscillating sector 123 whose movement is in turn transmitted, by a second horizontal link 124, to an oscillating sector 125 at the opposite side of the machine (Figs. II and IV) swingable about 80 the axis 86^a of the cam drum 86, (see also Figs. XXII and XXIII). The sector 125 carries a pawl 126 adapted to successively engage a starting notch 86^b, upstanding studs 86^c, 86^d, 86^e, and teeth 86^f at different circumferential points about the top of the cam drum 86, all as hereinafter explained. During operation of the knitting machine, the control or timing mechanism 85 is kept idle by a guard 127 that normally occupies the position 85 shown in Figs. XXII and XXIII in the path of a depending pin 126^a on pawl 126, thus holding the latter away from the cam drum 86. The guard 127 has the form of an arcuate plate, and is secured to the end of a substantially right-angled lever 128, freely fulcrumed on a fixed axis 129 on bracket 73, see Figs. XXII, XXIII and XXIII^a. The angled lever 128 has a drop arm 130 equipped at its free extremity with a laterally projecting stud 130^a that normally rides along the edge of the supplemental extension 114 of the main cam drum 16. Functioning of the control or timing mechanism 85 is dependent upon entry of the stud 130^a into a cam notch 100 131 in the supplemental extension 114 aforesaid, with impartation of movement to the angled lever 128 and lowering of the guard 127 thereon from the province of the depending pin 126^a on the oscillating pawl 126. 105 The pawl guard lever 128 is, however, also subject to the sub-control of the cam drum 87, of the mechanism 85—during the time that the lateral stud 130^a occupies the notch 131 in the supplemental extension 114 of the main 110 cam drum 16, and to this end, said lever is provided on the inside with a cam plate 132 adapted to be underridden by a radial stud 133, Fig. XXII, on said drum 87. Therefore, as long as the engagement between 115 the cam plate 132 and the cooperative stud 133 obtains, the oscillating pawl 126 will be temporarily held retracted or inactive. Incidental to such temporary inactivity of the 120 oscillating pawl 126, the function of actuating 130

the timing mechanism 85 is assumed by a spring urged pawl 134 that successively picks upstanding screw studs 87^b, 87^c and 87^d on the cam drum 87. The spring urged pawl 134 is pivoted to the end of an arm 135 which is free on the axis 87^a of the drum 87 and coupled by a link 136 for movement with the oscillating sector 125, hereinbefore referred to. The use of the two small inter-geared cam drums 86, 87 in the control mechanism 85, instead of a single one of larger diameter, not only conserves space, but saves time in the actuation of the various controlled instrumentalities. It is also to be particularly noted that the series of pawling projections on the drums 86, 87 is in each instance incomplete, the arrangement being such that one of the picking pawls 126, 134 may function during idle periods of the other.

Before the transfer ring R is lowered upon the needle cylinder 1 by the carrier 71, it is of course essential that the latch guard ring G be lifted out of the way. This function is accomplished automatically by the means shown in Figs. II, III, XLI and XLII at the instant of completion of the normal knitting cycle of the machine. As illustrated, the shaft 24 whereon the latch guard ring G is fulcrumed is constantly oscillated by an attached crank arm 137 (Fig. III) coupled by a link 138 with the eccentric pin 44^a of the gear wheel 44. Inward of the crank arm 137, the shaft 24 has secured to it a second arm 139 to the end of which is pivoted a hooked finger 140 that is normally held in the inactive position—of Fig. XLI—by a spring 141 so as to swing idly past a stud 142 at the side of the latch guard ring G. A pin 143 projecting from the tail of the hooked finger 140 normally swings back and forth above a horizontal trip member 144, but when said member is lifted as in Fig. XLI, the pin 143 is engaged to move the finger 140 upward thereby to catch the stud 142 and thus to initiate elevation of the latch guard ring G. To complete this movement, reliance is placed on a spring 145 (Fig. III) which is anchored at one end to the machine frame 3, and secured at the other to a hoop 146 engaging a grooved collar on the stud 142, said hoop serving as a convenient means of attachment capable of clearing the shaft 24, as said stud is swung to opposite sides of the latter, in the course of the movement of the latch guard ring G and thus yieldingly held in whatever position placed by the said spring 145. The trip member 144 is fulcrumed near its center to the upper end of a thrust rod 147, and is normally held in horizontal position against a stop 148 by a spring 149. The lower end of the thrust rod 147 rests upon the main cam drum 16, of the machine, so as to be longitudinally shiftable by a special lug 147^a thereon, see Fig. III.

It is also desirable, in order to insure per-

fect transfer, that the loops of the terminal course of the stocking blank be somewhat enlarged or dilated so as to facilitate entry thereinto of the points P of the transfer ring R. Such loop enlarging I accomplish with the aid of the sinkers S, and through special control of the cams by which the sinkers are actuated. To this end I replace the usual sinker cap ring of the machine by one such as indicated at 150 in Figs. IX, XXX, XXXI and XXXII, the same affording the actuating groove for the sinker butts, and carrying the center cam 151 as well as two flanking side cams 152, 153 which cooperate to shift the sinkers S relative to the needles N at the stitch points, in the usual manner during rotary and oscillatory knitting. Instead of being fixedly attached in accordance with prevalent practice, the flanking side cams 152, 153 are arranged for lateral shifting with respect to the center cam 151, and are accordingly provided with upstanding studs 154, 154^a and 155, 155^a that extend through radial guide slots in the cap ring 160. The protruding ends of the studs 154^a, 155^a engage in inclined cam slots 156, 158 respectively in an annulus 160, and the studs 154, 155 in inclined slots of separately attached plates 161, 162. The annulus 160 is circumferentially shiftable on the cap ring 150, the extent of such movement being limited by cooperation of a screw 163 and a slot 164. Except for slight adjustment to take up wear of the side cam 152, the plate 161 may be regarded as fixed to the annulus 160; but in order to secure an abnormal inward thrust of the sinkers S to enlarge the terminal loops of the fabric for the purpose of transfer, the plate 162 associated with the cam 153 is mounted for independent horizontal swinging movement about a fulcrum screw 165 in opposition to a leaf spring 163 tending to normally maintain it in the position of Fig. XXX. Swinging of the plate 162 is limited on the one hand by a stop 167, and on the other, by a set screw 168 which is adjustable in a stud 169 and cooperates with a lug 170 on said plate. The annulus 160 is normally held against circumferential movement by a latch 171 (Fig. XXXVI) engaging an opening 172 in it, said latch being pivoted to a stud post 173 upstanding from the sinker cap ring 150, and yieldingly held in the engaging position shown by a leaf spring 174 operative beneath the tail of the same. Manipulation of the annulus 160 and its adjuncts is controlled by the supplemental extension 114, of the main cam drum 16, through the medium of rods 175, 176, whereof the first carries in its lower end a lateral pin to cooperate with a cam groove 175^a (Fig. IV), while the latter is engaged by a lug 176^a in said supplemental extension 114. The rods 175, 176 are coupled with motion translating bell cranks 178, 179 which respectively connect with links 180, 181 whereof the

inner end of the former overlies the latter directly above the annulus 160. The link 180 has a longitudinal slot 182 for connection, with provision for a limited amount of lost motion, to a stud 183 upstanding from the annulus 160. The other link 181 carries a depending pin 184 for engaging the tail 162^a of the plate 162, and has its inner end bent at an inclination as at 181^a (Fig. XXXVI) for engaging a lug 171^a on the latch 171 to lift the latter when the annulus 160 is to be released as hereinafter explained.

To preclude the possibility of interference by the lifting or elevating picker 19 during bodily elevation of the needle cylinder 1, as described in connection with Figs. XX and XXI, I cause the same to be raised out of the way of the needle butts by a lever 189 fulcrumed about a fixed pivot 190. The inner 20 laterally-bent arm of this lever 189 engages beneath the picker 19 (Figs. XX and XXI), and its outer arm is coupled to a vertical pull rod 191 having a lateral stud 191^a at its lower end for cooperation with an internal cam 25 ridge 192 within the hollow of the supplemental extension 114 of the main cam drum 16. Accordingly, as long as the stud 191^a is engaged by the cam ridge 192, it will be apparent that the picker 19 will be held in an 30 elevated inactive position clear of the needle butts. A special guard cam 19^b in the vicinity of the other lifting or elevating picker 19^a (Figs. XIX and XX) prevents the needle butts from accidentally rising into engagement with said picker during elevation of the needle cylinder 1 incidental to transfer, as aforesaid.

Needle latch clearing, in accordance with my invention, is effected by a cam 185 which 40 is guided for vertical shifting from the full to the dotted line positions of Fig. XIX, in a notch 186 in the fixed portion C of the knitting cam shell. The movements of this cam 185 are governed, through the instrumentality of a bell crank lever 187, freely fulcrumed on the stud shaft 108, by a cam lug 188 on the main pattern or cam drum 16.

For the purpose of ejecting the fabric from the needle cylinder 1 and through the 50 transfer ring R for subsequent retainment by the latter after transfer of the terminal loops to the points P, I provide means as follows: Mounted for independent rotation axially of the cylindric head 76 of the carrier 71, is a 55 tubular prolongation 193 across the open outer end of which a pair of opposing bristled clamp brushes 194 abut. These clamp brushes 194 are supported by spring arms 195 so that they can yield relatively when penetrated by an ejector 196 (Fig. XLV) arranged to be thrust upwardly through the needle cylinder 1, the transfer ring R, and the tubular extension 193 of the carrier head 76 when these several elements are aligned, 60 as in Fig. IX. In order to obviate twisting

of the ejected fabric clamped between the brushes 194 during certain phases of the transfer operation, the tubular extension 193 is caused to rotate in unison with the needle cylinder 1 and the transfer ring R through 70 engagement of an upstanding tongue 197 of the presser plate 70 within the ring R, with a lug 198 on the periphery of said tubular extension, see Figs. IX and XIII. From Figs. I and XLV it will be observed that the 75 ejector 196 comprises a tube 196^a that is slideable telescopically over an axial stem 199. This stem 199 is pivoted at its lower end, as indicated at 199^a, to the bottom of a vertical bracket 200 dropped from the annulus 30 that 80 assists in sustaining the fabric receiver 29. A pin 201 projecting laterally from the ejector tube 196^a at its lower end, extends through a vertical guide slot in the bracket 200, and is coupled by a link 202 with the end of an 85 arm 203 fulcrumed for independent movement on the shaft 47^a hereinbefore referred to. The means 204 (Figs. II, IV, XLIII and XLIV) for swinging this arm 203 is similar to that described in connection with the 90 latch guard ring G in that it comprises a constantly oscillating member 205 (by virtue of being fast on the shaft 47^a) in the form of a sector whereto is pivoted a hooked finger 206 which is normally held, in the position of 95 Fig. XLIII, by a spring 207 so as to swing clear of a projecting pin 208 on the fulcrum hub member 209 of the arm 203. The moment of action of the means 204 is determined by the cam drum 86 of the timing means 85 and directly by the same cam 100 which causes depression of the transfer ring R relative to the carrier 71, when the latter is in its lowered position, and through a roller lever 210 (pivoted on the fulcrum of the 100 arm 101, Figs. XII and XIII, previously described) which is connected by a link 211 with an arm 212, also free on the shaft 47^a. When this arm 212 is moved counter-clockwise from the position of Fig. XLIII to that 105 of Fig. XLIV, it causes the hooked finger 206, by cooperation with the projection 206^a thereon, to be swung outward to engage the stud 208 on the lever 203, and through the interposed parts already explained, to effect 110 lifting of the ejector 196. This movement is extremely rapid and abrupt, and in order to counteract it with a view toward preventing injury to the ejector 196, I employ a 115 number of leaf springs 199^b (Fig. LV) which are retained in recessions along the axial rod 199 and bear against the inner surface of the telescoping outer tube 196^a. Accidental tripping of the mechanism 204 is prevented during the knitting cycle of the machine by a 120 lug 213, Figs. XXII and XXIII, on the underside of the cam drum 86 of timing means 85, such lug overlying a projecting pin 214 on the lever 210, see Figs. I, XXV, XXVI and XXVII. In order to be normally out 125 130

of the way of the fabric descending from the needle cylinder 1, the ejector 196 is ordinarily maintained in the inclined position of Fig. I, i. e., lying toward one side of the fabric receiver 29; but immediately preceding its elevation the same is swung inward on the pivot 199^a to the dot and dash line position of Fig. XVIII, by an arm 215 loosely embracing it at the upper end, said arm being fulcrumed at 216 to the side of the fabric receiver 29 and acted upon by a depending member 217 of the lever 210 (Figs. IV, XXII and XXIII) so as to be actuated simultaneously with dislodgement of the transfer ring R relative to the carrier 70. Return of the ejector 196 to the normal collapsed position is insured by a lateral pin 218 on the sector 205 of mechanism 204 (see Figs. IV, XLIII and XLIV) arranged to engage the rearwardly projecting end of the arm 203 as said sector moves through its clockwise stroke.

For the purpose of automatically starting the machine to press off the fabric after penetration of its loops by the points of the transfer ring R, the arm 203, in moving downward incidental to the collapsing of the ejector 196, strikes a pivoted finger 219 (Figs. I and IV). This finger 219 is connected by a chain 220 to a lever 221 fulcrumed at 222, Fig. I, to the front of the machine frame 3, and the movement of this lever is imparted to a link 223 that is coupled with the trigger 224 associated with the belt shipper lever 10. Thus as the trigger 224 is lifted, the shipper 10 is released to the action of its spring, and the belt 38 consequently automatically shifted from the loose pulley 8 to the tight pulley 7, by virtue of the flexibility of the chain 220, the finger 219 is allowed free movement without inducing motion of the lever 221 during the up stroke of the arm 203.

Starting of the machine to restore it to the original position to commence a new stocking is initiated during the final lifting of the transfer ring R from the needle cylinder 1, by a pin 225 on the gear sector 94 (Figs. XXVIII and XXIX) adapted to engage a trigger 226 on the contiguous end of the lever 221 (Fig. I) and to depress the same thereby tripping the belt shipper latch 224 as before. The trigger 226 is spring pressed upward for capacity to yield during counterclockwise movement of the gear sector arm of bell crank 94 without influencing the lever 221 at that time.

The operation of my automatic transfer mechanism in connection with a knitting machine of the Scott type is as follows:

Let it be taken for granted that a stocking blank has been knit complete with heel and toe pockets through rotation and oscillation of the needle cylinder 1, all in the customary manner. Also, let it be assumed that the completion of the final round of the knitting is attended by a last shifting of the main cam

drum 16 to effect, through its lug 23 and the associated thrust rod 22, withdrawal of the cam segment 21 (Fig. VII) to leave the needles N leveled and holding the terminal course of the fabric loops; the mechanism (Figs. XL and XLII) tripped to swing the needle latch guard ring G to the position of Fig. V through influence of lug 147^a (also on the main cam drum 16) upon the thrust rod 147 (Fig. III); the belt shipper 10 shifted to place belt 38 on the loose pulley 7 under influence of the projection 12^a of the rotary cam 12 (Fig. III) with the lug 10^a of said shipper 10, and the latter engaged by the latch 224 (Fig. I); and the lug 56 of lever 54 (Fig. III) engaged by the projection 57 on the supplemental cam 58 of the aforesaid shipper control cam 12. Now as a result of the last described movement of the lever 54, the pawls 48, 49 are released to activity to respectively pick the stud pins 50, 51 on the intermeshing drive gears 4, 52 and thus step about the needle cylinder 1, such action continuing for approximately two revolutions of the latter, as determined by gaps in the stud series 50, 51, within which the pawls 48, 49 are subsequently obliged to play idly. Concurrent with rotation of the needle cylinder 1, the lug 176^a on the supplemental extension 114 of the main cam drum 16 operates through the thrust rod 176 (Fig. IV) and intermediate connections, to shift the link 180 (Fig. XXXIII) and thereby causes swinging of the plate 162 about the pivot screw 165 to the position of Fig. XXXIV. The cam 153, in following the movement of the plate 162, is in its turn swung inward about the stud 155^a to the position of Fig. XXXIV. With this setting of the cam 153, the sinkers S are given an abnormal inward thrust (as will be appreciated by comparison of Fig. XXXIV with Fig. XXXIII, and Fig. XXXVIII with Fig. XXXVII) to enlarge or dilate the terminal course of loops held by the needles N. The step-wise rotation of the needle cylinder 1 just described will obviously be attended by picking of the rotary cam 12 of the belt shipper control (with concurrent movement of the main cam drum 16) by the mechanism provided in the machine for that purpose; and the timing is such that just as the needle cylinder 1 comes to rest, the lug 113 on the supplemental extension 114 engages the drop extension 115 of the finger 107, thereby actuating the latter to swing the yoke arm 110 (Fig. IV) and to advance the rods 112, 112^a (Figs. IX, XII and XIII) for simultaneous projection of the semicircular members 68, 68^a of the stripper T beyond the looping points P preparatory to descent of the transfer ring R upon the needle cylinder 1 of the machine, the pivoted latch 116, Figs. XII and XVI, incidentally engaging automatically with the notch 117 in the rod 112 to hold these several parts temporarily locked in the position described. Also, with the same

movement of the main cam drum 16, the pin 130^a on the depending extension 130 of lever 128 (Figs. IV, XXII, XXIII, and XXIII^a) enters the cam notch 131 of the supplemental extension 114 of the main cam drum 16 with the result that the guard 127 (Figs. XXII and XXIII) is dropped to release the pawl 126. This pawl 126 thereupon immediately engages the notch 86^b of the cam drum 86 to advance the elevating cam 88, Fig. XXIV, beneath the push rod 89, raising the latter, and, through the finger 90 (Figs. V, VII and VII^a), causing the pin 91 to enter the aperture in the bevel gear 27 to firmly lock the needle cylinder 1 against rotation temporarily. Lowering of the point ring carrier 71 (initiated during the first pick of the cam drum 86) is completed upon the second shog occasioned by engagement of the pawl 126 with the stud 86^c, through movement of the bell crank sector arm 94 induced by the cam groove 93 and through actuation of the intermeshing pinion 95 to turn said carrier. The second shog of the cam drum 86 is further attended by advancement of the elevating cam 98 on the companion drum 87 (by virtue of the inter-gearing) beneath the bolt 96 thereby shifting the latter upward to engage the tail 99 of the carrier arm 74, as in Fig. V. Also concurrent with the action just described, the arm 101, (Figs. XXII and XXIII) is engaged by the cam 100 of drum 86 with impartation of an upward thrust to the hooked rod 102, Fig. V such movement being transmitted to the swinging yoke arm 105 for displacement of the transfer ring R downward relative to the cylindric shell 76, from the position of Fig. IX to that of Fig. X, thus causing the points P to penetrate the fabric loops behind the needles N, the spring 106^a (Fig. XXV) serving at this time to urge the stripper T against the top of the sinkers S, and the transfer ring R to rest on said stripper, as in Fig. X. Now it will be further observed that simultaneously with the swinging of arm 101, the section 100^a, Figs. XXIII and XXIV, of cam 100 on drum 86 actuates the arm 210, which, through the link 211, trips the mechanism 204 (Figs. IV, XLIII and XLIV) so that upon the very next counter-clockwise movement of the oscillating sector 205, the finger 206 engages the stud 208 to swing the arm 203. This results in rise of the ejector 196 to displace the stocking from the machine so as to be clamped by the brushes 194 (Fig. IX) on the tubular extension 193 of the carrier head 76. The timing of the last two operations described, is such that the upward thrust of the ejector 196 follows immediately upon downward displacement of the transfer ring R. By the time all this is consummated, the radial stud 133 on drum 87 (Figs. XXII, XXIII and XXIII^a) is engaged beneath the cam plate 132 to lift the lever 128 with the guard 127 and thereby restrain activity of the pawl 126

while the actuation of the timing mechanism 85 is temporarily transferred to the pawl 134, movement of the drums 86, 87 having proceeded to the extent of advancing the elevating cams 88, 98 from beneath the rod 89 and bolt 96 to effect release of the needle cylinder 1 for rotation for a purpose to be presently explained.

At this stage of the transfer operation, the relation between the needles N, the sinkers S and the looping points P of the ring R is that shown in Fig. XXXVIII. The next step is to cause casting of the fabric loops from the needles N. This entails re-starting of the machine under drive of the belt 38, and is initiated automatically with collapse of the ejector 196 (Fig. IV) through engagement of its arm 203 with the finger 219, the induced pull on the chain 220 (Fig. I) imparting movement to the lever 221 and resulting in lifting the latch 224 to release the shipper 10 to its spring whereby the said belt 38 is carried to the tight pulley 7. The very first pick of the main cam drum 16 is attended by drop of the trust rod 22, (Fig. VIII) from the lug 23 to permit restoration of the knitting or stitch cams 18 to actuate the needles N during the ensuing revolution of the cylinder 1 and thereby cast the fabric loops. This action is so clearly depicted in Fig. XXXIX, as to obviate further detailed explanation, and the final result shown in Fig. XL wherefrom it will be seen that in rising subsequently, the needles N pass to the front of the fabric loops which are held only by the points P of the transfer ring R but still engaged in the notches of the sinkers S. Release of the loops is effected through retraction of the sinkers S to the position of Fig. XI instituted by action of the groove 175 on the main cam drum supplemental extension 114 upon the rod 175 (Fig. II) whose movement is imparted, through the interposed bell crank 179, to the link 181 (Fig. XXXII). As this link 181 moves forward, its inclined portion 181^a lifts the latch 171 (Fig. XXXVI) from the aperture 172 in annulus 160, so that in continued movement, the link 180 engages the stud 183 whereby said annulus is circumferentially shifted to the extent of causing withdrawal of the flanking side cams 152, 153 of the sinker actuating group as shown in Figs. XXXII and XXXV thereby permitting the sinkers S to remain in the retracted position away from the fabric loops to which position they are shifted by the center cam 151. As the sinkers S are retracted in the manner just explained, the transfer ring R is urged further downward (under action of a spring 106^a upon the cam 100 of drum 86, (Fig. XXV) with the stripper T thus yieldingly resting on and clamping the fabric against the lower ledges of the sinkers S in line with their fabric-engaging notches, all as in Figs. XI and XI_a.

It now remains to restore the transfer ring R to the original position in the head 76 of the carrier 71, to swing said carrier back to the normal position of Fig. I, and to restore the machine to condition for commencement of a new stocking. The first of these conditions is fulfilled by bodily movement of the needle cylinder 1 vertically (the needles remaining relatively stationary) as depicted in Fig. XI and in the manner shown in Fig. XVII. For this purpose, the belt 38 is again automatically shifted to the loose pulley 8 through engagement of the lug 12^b on rotary cam 12 (Fig. III) with the shipper 10, said cam having been shogged in proper sequence with preceding events by a pick of the pawl 60 upon the projection 61. With the same movement of the rotary cam 12, the projection 57^a on its supplemental portion 58 rides beneath the lug 56 and causes the arm 54 to be moved a second time to release the pawls 48, 49, so that picking of the gears 4, 52 for progression of the needle cylinder 1 follows in exactly the same manner as previously described. Incidental to such picking, the main cam drum 16, is advanced to bring about gradual or progressive raising of arm 33 (Fig. XVII) through the action of cam ridge 34, whereby the required vertical movement is imparted to the fabric receiver 29 and in turn to the transfer needle cylinder 1. The ring R with the loops of the terminal course of the fabric clamped between its stripper T and the sinkers S in being obliged to follow suit, is elevated to a height insuring complete clearance, and freeing of the fabric loops from contact behind the needles N as will be seen by referring again to Fig. XI, and restoration of the transfer ring R to original position in the carrier 71. Contemporaneous with the immediately foregoing operation, the roller of arm 101 still occupies the cam 100, which, at this time, recedes downwardly as required, thereby allowing the yoke arm 105 to follow the upward movement of the transfer ring R, the spring 106^a, in acting upon said cam 100, all the while offering yielding resistance to such movement. With the fabric now wholly transferred to the ring R and with the sinkers S still retracted as in Fig. XL, the carrier 71 is ready to be returned to the normal position of Fig. I. This action is initiated through fall of the arm 128 (Figs. IV, XXII and XXIII) occasioned by progression of the radial stud 133 beyond the cam 132 (the pawl 134 having in the interim successively picked the studs 87^b, 87^c to rotate the cam drum 87 for this purpose) and consequent release of the pawl 126 to activity for a second time. The latter pawl 126 thereupon immediately picks the teeth 86^c to rotate the cam drum 86 with the result that the bell crank sector 94 is swung in a direction opposite to that previously described, thereby

raising the transfer ring carrier 71 as required. Incidental to the last described movement of the cam drum 86, the cam 100 is advanced beyond the roller 101^a of arm 101, depression thereof being assured by the declination at 100^b (Figs. XXIII and XXIV) so that the yoke arm 105 (Fig. VI) is released to the influence of the spring 105^b (Fig. VI) to thereafter hold the transfer ring R up in the head 76 of the carrier 71. The timing mechanism 85 has now accomplished all its functions; and its complete restoration to the normal inactive position of Figs. XXII and XXIII, is brought about by a final pick of the pawl 134 upon the stud 87^d of cam drum 87. Concurrent with the return swing of the bell crank sector arm 94 (Fig. XXIX), the rearwardly projecting pin 225 thereon wipes past the trigger 226 (whose independent movement in the same direction is prevented by the cooperating stop pin 226^a) to actuate the lever 221, thereby causing lifting of the belt shipper latch 224 (Fig. I), and release of the shipper 10 to once more return the belt 38 to the tight pulley 7. Incidental movement of the main cam drum 16, occasioned as a result, brings the cam 34 (Fig. XVII) thereon beyond the province of lever arm 33 to allow the fabric receiver 29 and the needle cylinder 1—directly supported thereby—to drop to the normal lowered position. With a final shog of the rotary belt-shipper control-cam 12 (Fig. III), induced by engagement of the pawl 60 with the projection 62, the lug 12^b on said cam, throws the shipper 10 to shift the belt 38 to the loose pulley 8, in which position it is thereafter held by the latch 224. This completes the transfer cycle and leaves the machine in condition for starting of a new stocking (as shown in Figs. I, II, III and IV), all that remains for the operator to do is to first manually lower the needle latch guard ring G (to restore the feeds F), and then trip the belt shipper latch 224 which may be effected, simply, by depressing the left hand end of the lever 221 at the front of the machine (Figs. I and II). Removal of the transfer ring R together with the transferred stocking is facilitated with the aid of a lever 227 (Fig. I) which is pivoted at 228 to the bracket 73 and has a tail in the range of the pin 104 of the yoke arm 105. By depressing the lever 227, preferably with the right hand, it will be seen that the yoke arm 105 is actuated to dislodge the transfer ring R from the locking bolt 81, whereupon the ring may be grasped above the points P by the left hand and first rotated to register the notches 78 (Fig. XIV) with the pins 79, and finally bodily withdrawn without danger of loop dropping, the trailing portion of the stocking yielding to being readily pulled through the brushes 194 of the cylinder extension 193 of the carrier head 76 without un-

due straining. While a new stocking is being knit, the transfer ring R with the previous stocking blank, is placed in a sewing machine designed to close the toe pocket and when this work is finished, the empty ring R is returned to the knitting machine in readiness to receive the new stocking blank without entailing loss of time in the operation of the machine.

Coming now to the adaptation of my invention to a knitting machine of the Hemphill type (Figs. XLVI, XLVII, XLVIII and XLIX) it may be stated at the outset, that in the main, most of the parts thereof hereinbefore described in connection with the Scott machine, can be employed without requiring alteration, and any minor changes in others may be effected, in view of the disclosures already made, by any mechanic skilled in the art to which this invention pertains. For convenience, all corresponding standard parts in the Hemphill structure herein shown are identified with the same reference numerals previously employed. One of the outstanding characteristics of the Hemphill machine is that its needle cylinder 1 is stationary (except for capacity to rotate and oscillate), while its needle-actuating cam shell C (together with the retractable section 21 carrying the stitch cams 18) is movable vertically for fashioning purposes. As shown in Figs. XLVI and XLVIII, the cam shell C is supported by a plate 230 which is apertured as at 231 to clear the needle cylinder 1, and which has secured to it a depending bar 232. This bar 232 is slideable longitudinally in upper and lower guides 233, 234 respectively afforded by the machine frame. A laterally-extending bracket 235 secured to the bar 232 at a point intermediate the guides 233, 234, overhangs a rotary cam 236, which, in practice, carries a series of cam lugs (not shown) adapted to cooperate with registering pins 237 in the bracket aforesaid changing the operative relation between the sinkers S and the needles N to vary the length of the fabric loops as the knitting of the stocking proceeds. For the purposes of my invention, I attach to the rotary cam 236, a special cam segment 238 in line with one of the pins of the series 237, said segment being recessed at 239 to permit the bar 232, and the needle actuating cams 18 to drop below the normal position to bring the needles N to the level indicated in Fig. XLVI. Another differentiating characteristic of the Hemphill machine is that its cam shell C is equipped with a needle depressing cam 240 (Fig. XLIX) that I employ to advantage in connection with the transfer operation, as hereinafter noted.

Assuming the operations necessary in preparation for actual transfer up to the time that the transfer ring R is dislodged from the carrier head 76 and impressed upon the needle cylinder 1, as shown in Fig. XLVI, to have been accomplished by similar means and in an

identical manner to that described in connection with the Scott machine, the operations immediately following in the present connection are as follows: upon movement of the rotary cam 236 (Fig. XLVIII) and incidental sliding of the pin 237 into the notch 239 of special cam segment 238, the bar 232, in following, carries the plate 230 and the needle actuating cam shell C with it, so that concurrent with rotation of the needle cylinder, the cam 240 (Fig. XLIX) will function to bring the needles N down to the level indicated in Fig. XLVII entirely clear of the fabric loops on the points P of the transfer ring R, so that said ring may be withdrawn without danger of loop dropping, as the carrier 71 is swung to the normal retracted position. In the present instance the spring 105^b operative upon the yoke arm 105 may be relied upon to first restore the transfer ring R into the original position within the carrier head 76.

Having thus described my invention, I claim:

1. The method of transferring knitted fabric from the needles of a knitting machine which involves use of a transfer device with looping points, placement of said device with its points penetrating fabric loops on the needles, and relative bodily movement between the needles and the sustaining and guiding means therefor to subsequently free the loops and concurrently dislodge the transfer device with the transferred fabric from said needles.

2. The method of transferring knitted fabric from the needles of a knitting machine which involves the use of a transfer device with looping points, placement of said device to rest upon the sinkers of the machine with the points penetrating the loops on the needles, actuation of the needles to cast the loops from them, and relative bodily movement between the sinkers and needles to subsequently free the loops and concurrently dislodge the transfer device with the transferred fabric from said needles.

3. The combination with a knitting machine comprising needles and cooperative sinkers capable of bodily movement relatively for fashioning purposes; of transfer mechanism utilizing a similar movement of greater extent to free the fabric loops from contact with the needles during transfer.

4. The combination with a knitting machine comprising needles and cooperative sinkers capable of bodily movement relatively for fashioning purposes; of transfer mechanism utilizing a similar movement of greater extent to free the fabric loops from contact with the needles during transfer, and including a device with points for retaining the fabric loops so released.

5. The combination with a knitting machine comprising needles, cooperative sinkers, and knitting cams bodily movable relatively

to vary the operative relation between said needles and sinkers for fashioning purposes; of transfer mechanism utilizing a similar movement of greater extent to free the fabric loops from contact with the needles, and including a device for retaining the fabric loops so released.

6. The combination with a knitting machine comprising needle sustaining and guiding means capable of bodily movement; of transfer mechanism including a device with points registerable with the needles to penetrate fabric loops on them, and utilizing the bodily movement of the needle sustaining and guiding means to dislodge the device aforesaid with the transferred fabric.

7. The combination with a knitting machine comprising needles, cooperative sinkers, and means controlling relative bodily movement of the needles and sinkers for fashioning purposes; of transfer mechanism including a device with points registerable with the needles to penetrate fabric loops on them, and means coordinated with the fashioning control to move the sinkers and needles relatively for the further purpose of freeing the loops from contact with the latter for retainment by the points of the transfer device.

8. The combination with a knitting machine comprising a needle cylinder capable of bodily movement axially; of transfer mechanism including a ring with points registerable with the needles to penetrate fabric loops on them, said mechanism utilizing the bodily movement of the cylinder to dislodge the ring from the needles for retainment of the fabric loops by its points.

9. The combination with a knitting machine comprising needles and cooperative sinkers; of transfer mechanism including means for moving the sinkers as a whole relative to the needles to free the fabric loops from contact with the latter.

10. The combination with a knitting machine comprising needles and cooperative sinkers; of transfer mechanism including a device with points registerable with the needles to penetrate fabric loops on them, and means for moving the sinkers as a whole relative to the needles to free the fabric loops from contact with the latter for retainment by the points of said device.

11. The combination with a knitting machine comprising needle sustaining and guiding means; of transfer mechanism including a device with points registerable with the needles to penetrate fabric loops on them, and means for bodily moving the needle sustaining and guiding means to dislodge the device aforesaid from the needles for retainment of the fabric loops by its points.

12. The combination with a knitting machine comprising needles and cooperative sinkers; of transfer mechanism including a

device with points registerable with the needles to penetrate fabric loops on them while resting on said sinkers, and means for bodily moving the sinkers together with the transfer device relative to the needles to free the fabric loops from the latter for retainment by the looping points of said device.

13. The combination with a knitting machine comprising needles and cooperative sinkers; of transfer mechanism including a device with points registerable with the needles to penetrate fabric loops on them while resting on the sinkers, and means for bodily moving the sinkers to raise the transfer device and the transferred web clear of the needles.

14. The combination with a knitting machine comprising needles, means for sustaining and guiding them, and knitting cams to actuate them; of transfer mechanism including a device with points registerable with the needles to penetrate fabric loops on them, and means for bodily moving the knitting cams and the means for sustaining and guiding the needles relatively to free the fabric loops from contact with the needles to insure their retainment by the points of said device.

15. The combination with a knitting machine comprising needles, means for sustaining and guiding them, knitting cams to actuate them, and cooperative sinkers carried by said sustaining and guiding means; of transfer mechanism including a device with points registerable with the needles while resting upon the sinkers, and means for bodily moving the needle sustaining and guiding means and the knitting cams relatively to alter the relation between the sinkers and the needles for the purpose of freeing the fabric loops from contact with the latter to insure their retainment by the points of said device.

16. The combination with a knitting machine comprising needles and cooperative sinkers; of transfer mechanism including a transfer device with looping points, means to move the transfer device to register and engage its points individually with the needles, and means for moving the sinkers as a whole relative to the needles to release the fabric loops from the latter for retainment by the points of said transfer device.

17. The combination with a knitting machine comprising needles and cooperative sinkers; of transfer mechanism including a transfer device with looping points, a carrier for moving said transfer device into position adjacent the needles, means to displace the transfer device from the carrier to rest against the sinkers with the points engaging the needles and penetrating the fabric loops on them; and means to bodily move the sinkers and the transfer device relative to the needles to effect release of the fabric loops from contact with the latter

- for retainment by the looping points, and to restore said device to its original position in the carrier.
18. The combination with a knitting machine comprising a needle cylinder and means to normally rotate it to produce tubular fabric; of transfer mechanism adapted to function after completion of the knitting cycle including auxiliary drive means comprising a pair of pawls alternately operating to cause progressive rotation of the needle cylinder during certain phases of the transfer operation.
19. The combination with a knitting machine comprising a needle cylinder, and a gear coordinated with its drive shaft to normally rotate the cylinder; of transfer mechanism adapted to function after completion of the knitting cycle comprising a companion gear in mesh with the gear aforesaid, and a pair of alternately operative pawls to respectively pick the intermeshing gears with impartation of progressive rotation to the needle cylinder during certain phases of the transfer operation.
20. The combination with a knitting machine comprising a needle cylinder, drive mechanism therefor including tight and loose pulleys, and a belt shipper control; of transfer mechanism including auxiliary means for rotating the cylinder after completion of the normal knitting cycle, and means subject to the belt shipper control for rendering the auxiliary drive active simultaneously with shifting of the belt to the loose pulley.
21. The combination with a knitting machine comprising a needle cylinder and drive means therefor; of transfer mechanism including auxiliary drive means operative upon completion of the normal knitting cycle including a pair of alternately operative pawls to effect intermittent rotation of the needle cylinder for transfer purposes, and means for normally holding said pawls idle during the normal knitting cycle.
22. The combination with a knitting machine comprising a needle cylinder, drive mechanism embodying tight and loose pulleys, and a belt shipper, and a rotating cam to control said shipper; of transfer mechanism including an auxiliary drive for rotating the cylinder for transfer purposes after completion of the normal knitting cycle including a pawl, means to normally hold the pawl idle during the knitting period, and said latter means being subject to the belt shipper control for actuation to release the pawl concurrently with shifting of the belt to the loose pulley.
23. The combination with a knitting machine comprising a needle cylinder and drive mechanism therefor embodying tight and loose pulleys, a belt shipper, and a rotating cam to control said shipper; of transfer mechanism including auxiliary drive means to rotate the cylinder for transfer purposes after completion of the normal knitting cycle, said means comprising a pawl, a lever to normally hold the pawl idle during the knitting cycle, and a cam rotating with the belt shipper control cam aforesaid for actuating the lever to release the pawl concurrently with shifting of the belt to the loose pulley.
24. The combination with a knitting machine comprising a needle cylinder; of transfer mechanism including a transfer ring with looping points, a movable carrier with a tubular head to receive the transfer ring, pin and transfer groove means to retain the ring rotatively in the head, and auxiliary locking means to prevent rotation of said ring while the carrier is manipulated to engage the points with the needles.
25. The combination with a knitting machine comprising a needle cylinder; of a transfer ring, a swingable carrier with a tubular head to receive the transfer ring, pins on said carrier adapted to engage a circumferential groove in the ring to rotatively retain the latter, and a spring-influenced locking bolt adapted to automatically engage a notch in the ring upon slight turning incidental to mounting in the carrier, thereby to prevent rotation of said ring while the carrier is manipulated to engage the points with the needles.
26. The combination with a knitting machine comprising a needle cylinder; of transfer means including a ring with looping points, a movable carrier with a tubular head to receive the transfer ring, pin and groove means to retain said ring rotatively in the carrier head, locking means cooperating to normally hold the transfer ring against rotation during the movement of the carrier to insure proper registry of the looping points with the needles, means for subsequently displacing the transfer ring in the carrier to engage its points with the needles and at the same time to release it from the locking means so as to be free to subsequently rotate with the needle cylinder.
27. The combination with a knitting machine comprising a needle cylinder; of transfer mechanism including a transfer ring with looping points, a movable carrier with a tubular head to receive said ring, a yoke lever fulcrumed to said carrier and equipped with diametric pins for engaging a circumferential groove in the transfer ring to rotatively retain it in the carrier, means for locking said ring against rotation to insure proper registry between the looping points and the needles as the carrier is moved to active position, and means to subsequently actuate the yoke arm aforesaid to displace the transfer ring in the carrier for the purpose of engaging the looping points with the needles and to incidentally release said ring from the lock.

means for capacity to subsequently rotate with the needle cylinder.

28. The combination with a knitting machine comprising needles and cooperative 5 sinkers; of transfer mechanism including a transfer device with looping points and a shiftable stripper, movable means to position the transfer device relative to the needles, means to automatically advance the stripper 10 with respect to the looping points to assist alignment of the latter and the needles and to so lock it prior to movement of the positioning means aforesaid, and means operative subsequently to release the stripper for capacity 15 to recede in contacting with the sinkers as the points of the transfer device are advanced to penetrate the fabric loops on the needles.

29. The combination with a knitting machine comprising needles and cooperative 20 sinkers, of transfer mechanism including a transfer device with looping points and a shiftable stripper, movable means to position the transfer device relative to the needles, automatic means including a push rod to advance the stripper with respect to the looping 25 points prior to movement of the positioning means aforesaid for capacity to assist in aligning the points and the needles, a spring-influenced latch to incidentally engage a notch 30 in the push rod to hold the stripper temporarily locked in advanced position, and means to subsequently withdraw the latch to release the stripper for capacity to recede in 35 contacting with the sinkers as the points of the transfer device are advanced to penetrate the fabric loops on the needles.

30. The combination with a knitting machine comprising needles and cooperative sinkers, of transfer mechanism including a transfer device with looping points and a shiftable stripper, a carrier to position the transfer device relative to the needles, means to automatically advance the stripper with respect to the looping points to assist aligning 45 of the latter with the needles and to so lock it during movement of the carrier, means to displace the transfer device from the carrier to engage its points with the needles and penetrate the fabric loops on them, and means to 50 incidentally release the stripper for capacity to recede in contacting with the sinkers.

31. The combination with a knitting machine comprising needles and cooperative sinkers, of transfer mechanism including a transfer device with looping points and a shiftable stripper, a movable carrier to position the transfer device relative to the needles, automatic means including a push rod to advance the stripper with respect to the looping 55 points prior to positioning movement of the carrier for capacity to assist in aligning the points and the needles, a spring influenced latch to incidentally engage a notch in the push rod to hold the stripper temporarily 60 locked in advanced position, an arm to dis-

place the transfer device from the carrier to engage its points with the needles and penetrate the fabric loops on them, and means operable by said arm to incidentally withdraw the latch thereby to release the stripper for 70 capacity to recede in contacting with the sinkers.

32. The combination with a knitting machine comprising needles; of transfer mechanism including a transfer device with looping points, means for manipulating the transfer device relative to the needles incidental to fabric transfer, and automatic timing means embodying a pair of intergeared cam drums between which the control of the functions incident to manipulation is divided, and means to intermittently progress the drums alternately for the purpose specified. 75

33. The combination with a knitting machine comprising needles; of transfer mechanism including a transfer device with looping points, means for manipulating the transfer device relative to the needles incidental to fabric transfer, and automatic timing means embodying a pair of intergeared cam 80 drums between which the control of the functions incident to manipulation is divided, a pawl associated with each drum, and means determining activity of the pawls to intermittently progress the drums alternately for the 85 purpose specified.

34. The combination with a knitting machine comprising needles; of transfer mechanism including a transfer device with looping points, means for manipulating the transfer device relative to the needles incidental to fabric transfer, and automatic timing means embodying a pair of intergeared cam drums between which the control of the functions incident to manipulation is divided, a pawl associated with each drum, means to oscillate the pawls in unison, and means determining activity of the pawls to intermittently progress the drums alternately for the purpose 90 specified. 100

35. The combination with a knitting machine comprising needles; of transfer mechanism including a transfer device with looping points, means for manipulating the transfer device relative to the needles incidental to fabric transfer, and automatic timing means embodying a pair of intergeared cam drums between which the control of the functions incident to manipulation is divided, a pawl associated with each drum to pick a series of projections thereon, and said series of projections being incomplete in each instance to enable functioning of one pawl during idle periods of the other in alternately progressing drums for the purpose specified. 115

36. The combination with a knitting machine comprising needles; of transfer mechanism including a transfer device with looping points, means for manipulating the transfer device relative to the needles incidental to 120

5 fabric transfer, and automatic timing means embodying a pair of intergeared cam drums between which the control of the functions incident to manipulation is divided, a pawl associated with each drum, and means actuated by one of said drums to govern activity of the pawl associated with the other drum.

10 37. The combination with a knitting machine comprising needles; of transfer mechanism including a transfer device with looping points, means for manipulating the transfer device relative to the needles incidental to fabric transfer, and automatic timing means embodying a pair of intergeared cam drums between which the control of the functions incident to manipulation is divided, a pawl associated with each drum, and a guard 15 activity of the pawl associated with the other actuated by one of said drums to govern activity of the pawl associated with the other drum.

20 38. The combination with a knitting machine comprising needles; of transfer mechanism including a transfer device with looping points, means for manipulating the transfer device relative to the needles incidental to fabric transfer, an automatic timing means embodying a pair of intergeared cam drums between which the control of the functions incident to manipulation is divided, a pawl associated with each drum to pick a series of 25 projections thereon; said series of projections being in each instance incomplete to enable functioning of one pawl during idle periods 30 of the other in alternately progressing the drums, and means actuated by one of said drums to govern activity of the pawl associated with the other drum in regulating drum progression.

35 39. The combination with a knitting machine comprising needles and associated knitting instrumentalities, as well as a main control means to govern them; of transfer mechanism including a transfer device with looping points, means for manipulating the transfer device relative to the needles incidental to fabric transfer, an automatic timing means embodying a pair of intergeared cam drums between which control of the functions incident to manipulation are divided, a pawl associated with each drum, governing means 40 subject to the main control means aforesaid of the machine in initiating picking by one of said pawls, and means whereby the other 45 of the drums subsequently actuates said governing means to render the same pawl temporarily inactive in regulating actuation of said timing means.

50 40. The combination with a knitting machine comprising needles and cooperative sinkers; of transfer mechanism including a transfer device with points registrable with the needles to penetrate fabric loops on them while resting against the sinkers, means to 55 yieldingly hold the transfer device in such

position; means to move the sinkers bodily in opposition to the yielding means aforesaid and relative to the needles to effect release of the fabric loops from contact with the latter for retainment solely by the points of the transfer device.

41. The combination with a knitting machine comprising needle and cooperative sinkers; of transfer mechanism including a transfer device with looping points, a carrier for positioning the transfer device adjacent the needles, means for displacing said transfer device in the carrier to rest, with capacity for yielding, against the sinkers with the points engaging the needles and penetrating the fabric loops on them, and means to move the sinkers bodily in opposition to the displacing means aforesaid and relative to the needles, thereby to effect release of the fabric loops from contact with the latter for retainment solely by the points of the transfer device, and restoration of said device to its original position in the carrier.

42. The combination with a knitting machine comprising needles and cooperative sinkers; of transfer mechanism including a transfer device with looping points, a carrier for positioning the transfer device adjacent the needles, a spring-influenced cam effective to displace the transfer device in the carrier to rest yieldingly against the sinkers with its points engaging the needles and penetrating the fabric loops on them, and means to move the sinkers bodily in opposition to the spring influenced cam aforesaid and relative to the needles, thereby to effect release of the fabric loops from contact with the latter for retainment solely by the points of the transfer device, and restoration of said device to its original position in the carrier.

43. The combination with a knitting machine comprising needles and cooperative sinkers; of transfer mechanism including a transfer device with looping points, a carrier for positioning the transfer device adjacent the needles, a rotary drum having a circumferential spring-influenced cam adapted to effect displacement of the transfer device in the carrier to rest yieldingly against the sinkers with the points engaging the needles and penetrating the fabric loops on them, and means to move the sinkers bodily in opposition to the spring influencing the cam aforesaid and relative to the needles, thereby to effect release of the fabric loops from contact with the latter for retainment solely by the points of the transfer device, and restoration of said device to its original position in the carrier.

44. The combination with a knitting machine comprising a needle cylinder; of transfer mechanism including an ejector to displace fabric from the cylinder, and yielding means penetrable by said ejector to grasp and hold the ejected fabric.

45. The combination with a knitting machine comprising a needle cylinder; of a transfer ring with points adapted to register with the needles to receive the fabric loops therefrom, an ejector to displace the fabric from the cylinder and through the transfer ring aforesaid, and yielding means penetrable by the ejector to grasp and hold the ejected fabric. 70
- 10 46. The combination with a knitting machine comprising a needle cylinder; of transfer mechanism including a transfer ring with looping points adapted to register with the needles to receive the fabric loops therefrom, means for supporting the transfer ring in alignment with the needle cylinder, a tubular member sustained by said supporting means in co-axial relation with the transfer ring, and yielding means carried by the tubular member penetrable by the ejector to grasp and hold the ejected fabric. 75
- 15 47. The combination with a knitting machine comprising a needle cylinder; of transfer mechanism including a transfer ring with points adapted to register with needles to receive the fabric loops therefrom, means to support the point transfer ring in alignment with the needle cylinder, a tubular member sustained by the supporting means in co-axial relation with the transfer ring, and a pair of opposed brushes yieldingly supported across the tubular member and penetrable by the ejector to grasp and hold the ejected fabric. 80
- 20 48. The combination with a knitting machine having a needle cylinder; of transfer mechanism including an ejector to displace fabric from the cylinder, and yielding means penetrable by said ejector to grasp and hold the ejected fabric, said yielding means having capacity to rotate freely for subsequent rotative movement with the needle cylinder to prevent incidental twisting of the fabric. 85
- 25 49. The combination with a knitting machine comprising a needle cylinder; of transfer mechanism including a transfer ring with points adapted to register with needles to receive the fabric loops therefrom, means to support the transfer ring in alignment with the needle cylinder, a tubular member sustained by the supporting means in co-axial relation with the transfer ring, and a pair of opposed brushes yieldingly supported across the tubular member and penetrable by the ejector to grasp and hold the ejected fabric, and coupling means whereby the tubular member is subsequently rotated with the transfer ring to prevent twisting of the fabric. 90
- 30 50. The combination with a knitting machine comprising a needle cylinder; of transfer mechanism including an ejector to displace fabric through said cylinder, said ejector having the form of a rod pivoted at the lower end and normally occupying a tilted position beneath the needle cylinder out of the way of the descending fabric, and means to swing the rod about its pivot to align it with said opening through the cylinder before projection for the purpose aforesaid. 95
- 35 51. The combination with a knitting machine comprising a needle cylinder, of transfer mechanism including an ejector to displace fabric through said cylinder, said ejector having the form of a rod pivoted at the lower end and normally occupying a tilted position beneath the needle cylinder out of the way of the descending fabric, and a laterally moving arm engaging the ejector above the pivot to swing it into alignment with the opening through said cylinder before projection for the purpose aforesaid. 100
- 40 52. The combination with a knitting machine comprising a needle cylinder, of transfer mechanism including an ejector to displace fabric through said cylinder, said ejector being composed of telescoping parts, and means to extend the ejector for the purpose aforesaid. 105
- 45 53. The combination with a knitting machine comprising a needle cylinder, of transfer mechanism including an ejector adapted to be abruptly thrust through said cylinder to displace the fabric therefrom, said ejector being composed of telescoping parts, and, means imposing restraint on the movement of said parts to counteract the effect of the abrupt thrust. 110
- 50 54. The combination with a knitting machine comprising a needle cylinder, of transfer mechanism including an ejector adapted to be abruptly thrust through the cylinder to displace the fabric therefrom, said ejector being composed of telescoping parts, and leaf springs imposing frictional restraint on the movement of said parts to counteract the effect of the abrupt thrust. 115
- 55 55. The combination with a knitting machine comprising a needle cylinder, and drive mechanism therefor with stop control; of transfer mechanism including an ejector to displace fabric from the needle cylinder, and means whereby, upon its return movement, said ejector causes actuation of the stop control aforesaid to automatically start the machine after fabric ejection. 120
- 60 56. The combination with a knitting machine comprising a needle cylinder, and drive mechanism therefor including tight and loose pulleys and a belt shipper; of transfer mechanism including an ejector to displace fabric from the needle cylinder, and means whereby, upon its return movement, said ejector causes actuation of the belt shipper aforesaid to shift the belt from the loose to the tight pulley to automatically start the machine after fabric ejection. 125
- 65 57. The combination with a knitting machine comprising a needle cylinder, and drive mechanism therefor including tight and loose 130

- pulleys, a spring-influenced belt shipper, and control means to shift said shipper to the loose pulley upon completion of the knitting cycle; of transfer mechanism including an 5 ejector to displace fabric from the needle cylinder, a latch to hold the belt shipper with the belt on the loose pulley during operation of the ejector, and means whereby, upon its return movement, said ejector causes withdrawal 10 of the latch to automatically release the shipper to its spring with consequent shifting of the belt to the tight pulley and restarting of the machine after fabric ejection.
- 15 58. The combination with a knitting machine comprising needles and cooperative sinkers; of transfer mechanism including a transfer device with looping points, and automatic means operative after completion 20 of the knitting cycle to effect the following functions in the order named: positioning of the transfer device to rest against the sinkers with its points penetrating the fabric loops on the needles, actuation of the needles 25 to cast the loops, and bodily movement of the sinkers and needles relatively to free the fabric loops while separating the needles and the transfer device.
59. The combination with a knitting machine 30 comprising needles and cooperative sinkers; of transfer mechanism including a transfer ring with looping points, and automatic means operative after completion of the knitting cycle to effect the following 35 functions in the order named: positioning of the transfer device to rest against the sinkers with its points penetrating fabric loops on the needles, actuation of the needles to cast the fabric loops, withdrawal of the sinkers 40 from the loops, and bodily movement of the sinkers and needles relatively to free the fabric loops while separating the needles and the transfer device.
60. The combination with a knitting machine 45 comprising needles and cooperative sinkers; of transfer mechanism including a transfer device with looping points; and automatic means operative after completion of the knitting cycle to effect the following 50 functions in the order named; dilation of the loops on the needles by abnormal inward thrust of the sinkers, positioning of the transfer device to rest against the sinkers with its points penetrating fabric loops 55 on the needles, actuation of the needles to cast the loops, withdrawal of the sinkers away from the fabric loops, and bodily movement of the sinkers and needles to free the fabric loops from the needles while separating 60 the latter and the transfer device.
61. The combination with a knitting machine comprising needles, cooperative sinkers, a latch guard for the needles, and means to automatically stop the machine after completion 65 of the knitting cycle; of transfer 70 means including a device with looping points, and automatic means functioning to effect latch clearing, needle leveling and latch guard withdrawal concurrent with completion of the normal knitting cycle, and immediately subsequent thereto, to further effect in the order named: dilation of the loops on the needles by abnormal inward thrust of the sinkers, positioning of the transfer device to rest against the sinkers with its 75 points penetrating the fabric loops on the needles, actuation of the needles to cast the fabric loops, withdrawal of the sinkers from the fabric loops, and bodily movement of the sinkers and the needles relatively to free 80 the fabric loops from the needles while separating the latter and said transfer device.
62. The combination with a knitting machine comprising needles, cooperative sinkers, a latch guard for the needles and means 85 to automatically stop the machine after completion of the knitting cycle; of transfer means including a transfer device comprising looping points and a shiftable stripper, and automatic means functioning to effect latch 90 clearing, needle leveling, and latch guard withdrawal concurrent with the completion of the knitting cycle, and immediately subsequent thereto to further effect in the order named: projection of the stripper relative to 95 the looping points of the transfer device to serve as means for aligning said points and the needles subsequently, temporary locking of the stripper, positioning the transfer device relative to the needles, advancing the transfer device to rest on the sinkers with its points penetrating the fabric loops on the needles and concurrently releasing the stripper for capacity to recede, actuation of the needles to cast the fabric loops, withdrawal 100 of the sinkers from the fabric loops, and bodily movement of the sinkers and needles relatively to free the fabric loops from the needles while separating the latter and said transfer device.
63. The combination with a knitting machine comprising a needle cylinder and cooperative sinkers; of transfer mechanism including a transfer device with looping points, and automatic means operative after completion 115 of the knitting cycle to effect the following functions in the order named: positioning of the transfer device relative to the needles with its points penetrating the fabric loops on them, ejection of the fabric from the 120 needle cylinder for retention by the transfer device, actuation of the needles to cast the fabric loops, and movement of the sinkers as a whole relative to the needles to free the fabric loops while separating said needles and 125 the transfer device.
64. The combination with a knitting machine comprising a needle cylinder, cooperative sinkers, a latch guard for the needles and means to automatically stop the machine 130

after completion of the knitting cycle; of
transfer means including a device with loop-
ing points, and automatic means to effect
latch clearing, needle leveling and latch
5 guard withdrawal concurrent with the com-
pletion of the normal knitting cycle; and im-
mediately subsequent to said operations to
further effect in the order named: dilation of
the loops on the needles by abnormal inward
10 thrust of the sinkers, positioning of the
transfer device to rest against the sinkers
with its points penetrating the fabric loops
on the needles, ejection of the fabric from the
needle cylinder for retainment by the trans-
fer device, actuation of the needles to cast 15
the fabric loops, withdrawal of the sinkers
away from the impaled fabric loops, and
bodily movement of the sinkers and the
needles relatively to free the fabric loops from
the needles while separating the latter and 20
said transfer device.

In testimony whereof, I have hereunto
signed my name at Philadelphia, Pennsyl-
vania, this 28th day of November, 1925.

LOUIS N. D. WILLIAMS.
